UNITED STATES PATENT OFFICE.

WILLIAM A. HATCHER, OF DETROIT, MICHIGAN, ASSIGNOR TO WERNICKE-HATCHER PUMP COMPANY, OF GRAND RAPIDS, MICHIGAN, A CORPORATION OF MICHIGAN.

VANE FOR ROTARY PUMPS OR ROTARY ENGINES.

Application filed February 19, 1921. Serial No. 446,469.

This invention relates to improvements in vanes for rotary pumps or rotary engines.

The object of the invention is to provide an improved vane with yielding means interposed within the same whereby the vane will be held seated against the adjacent part to form and maintain a tight joint.

Objects which pertain to details of construction and operation will definitely appear from the detailed description to follow.

I accomplish the object of my invention by the devices and means described in the following specification. The invention is clearly defined and pointed out in the claims.

A structure which is a preferred embodiment of my invention is fully illustrated in the accompanying drawing, forming a part of this specification, in which my improved vane is shown in position in my improved pump made the subject matter of a concurrent patent application.

Fig. I is a longitudinal detail sectional view through a portion of such pump, taken on line 1—1 of Fig. III, showing my said improved pump with vane in position.

Fig. II is an enlarged detail sectional view through my improved vane taken on line 2—2 of Fig. I, the vane only being shown.

Fig. III is a detail transverse sectional view on line corresponding to line 3—3 of Fig. I, showing the relation of my improved vane to the cylinder and the piston walls of such a pump.

In the drawing the sectional views are taken looking in the direction of the little arrows at the ends of the section lines and similar numerals of reference refer to similar parts throughout the several views.

Considering the numbered parts of the drawing, my improved vane 1 is made up of opposed symmetrical plate-like halves 2, 3. The half 3 has a bar 5 secured to the margin thereof by suitable rivets and the half 2 is cut away to correspond to the same, and the half 2 has the bar 4 riveted to its opposite symmetrical margin, the half 3 being cut away to accommodate the same, so that the two halves of the vane are capable of expansion in facial contact the one with the other in the plane of the vane. Semi-cylindrical cavity 7 is formed in the half 3 and opposed to the same in the half 2 is a cor-

responding semi-cylindrical cavity 6. These are disposed centrally but slightly at one side of the center, so that when the halves are brought together these parts do not register, there being a greater distance from the block or bar secured to the edge than from the opposite edge. The spring 8 is disposed in these recesses and the plates constituting the vane are pushed outwardly in the plane of the vane into yielding contact on opposite sides with the cylinder heads.

At the inner end of the half 3 are outwardly projecting lugs 9, 9, and precisely corresponding lugs 10, 10, are on the said half 2. In practice the outer end of the vane 1 contacts with the inner surface of the pump cylinder 11, and the outwardly projecting lugs 9 and 10 engage the cylinder heads 12 and 13 in the slots 14 and 15 respectively (see Fig. I). These slots are transverse to the plane of the said vane to maintain the same in contact with the cylinder wall.

The vane 1 is disposed in a recess 17 in a radial wall 18 within the piston 16, the radial wall 18 being counterbalanced at 19 (see Fig. III). A flat surface 20 is provided in the cylinder 11 for contact with the outer end of the vane 1. Contact is maintained by the lugs 9 and 10 engaging within the transverse slots 14 and 15 above described. However, where the pump revolves, as appears in my concurrent patent application, centrifugal force will hold the vane in contact with the inner wall of the cylinder and the lugs may be omitted.

I have not described the connections or ports to the pump in this behalf, as this invention pertains particularly to the vane. I have merely described it in this connection so that it may be readily understood what is accomplished in this particular structure. The lugs 9 and 10 are of great consequence in certain structures, but the parts may be maintained in contact by centrifugal force. In a rotary pump where the entire parts revolve at high speed these lugs may be dispensed with.

Having thus described my invention what I claim as new and desire to secure by Letters Patent is:

1. A vane for a rotary pump or engine comprising a pair of plates slidably overlapping each other in transverse planes, and

resilient means for relatively moving said plates in the direction of the line of intersection of said planes.

2. A vane for a rotary pump or engine comprising a pair of plates having a slidable sealing engagement with each other in transverse planes, the adjacent faces of said plates being recessed, and a spring located in said recess for relatively moving said plates in 10 the direction of the line of intersection of said planes.

3. In a rotary pump or engine, the combination with eccentrically revolvable cylinder and piston, of a vane for bridging the 15 space between said cylinder and piston slidable in a recess in one of said members, said vane comprising a pair of plates slably overlapping each other in transverse planes, and means for relatively moving said plates 20 in the direction of the line of intersection of said planes.

4. In a rotary pump or engine, the combination with a radially slotted piston and a cylinder in eccentric relation thereto having 25 parallel cheek plates at opposite ends of the piston, of a vane located in the slot in said piston and comprising a pair of plates slably overlapping each other in planes transverse to each other said planes having 30 their line of intersection parallel to the axis of said piston, and means for resiliently relatively moving said plates parallel to the axis of the piston to maintain sealing contact with said cheek plates.

35 5. In a rotary pump or engine, the combination with an eccentrically revolvable piston and cylinder, of a vane bridging the space between said piston and cylinder and slidable in a radial recess in one of said 40 members, and means for maintaining sealing contact between said vane and the complementary walls for the space between said piston and cylinder and also with the walls of the slot in which it is located.

6. In a rotary pump or engine, the combination with a piston and a cylinder eccentrically revolvable in fixed angular relation to each other, of a vane radially slidable in a slot in one of said members and bridging the space between the same and the other of 50 said members, the unslotted member having a portion of its wall perpendicular to the plane of said vane in sliding contact with the edge of the vane, said vane comprising a pair of members slably overlapping each other in transverse planes having their line of intersection parallel to the axes of said cylinder and piston, resilient means for relatively moving said plates in the direction of intersection of said planes to maintain the 60 same in sealing contact with the side walls of said cylinder.

7. In a rotary pump or cylinder, the combination with a cylinder and piston eccentrically revolvable at the same angular speed, 65 of a vane radially slidable in a slot in one of said members and bridging the space between said member and the other member, the unslotted member having a portion of its wall perpendicular to the plane of said 70 vane in sliding contact with the edge of the vane, said vane comprising a pair of plates slably overlapping each other in transverse planes having their line of intersection parallel to the axes of said cylinder and piston, 75 and the contacting faces of said plates being provided with registering recesses, a spring located in said recesses for yieldably pressing said plates in opposite directions 80 and maintaining the side edges thereof in sealing contact with the side walls of the cylinder, and means for also maintaining the transverse edge of said plate in sealing contact with the surface over which it slides.

In witness whereof I have hereunto set my hand.

WILLIAM A. HATCHER.
